BATHTUB DRAIN AND SUMP

Dwight La Barre, Detroit, Mich., assignor to Borg-Warner Corporation, Chicago, Ill., a corporation of Illinois

Application April 26, 1947, Serial No. 744,270

8 Claims. (Cl. 4—190)

1

The present invention relates generally to bathtubs, basins, and the like, and it has more particular reference to a bathtub drain and sump assembly.

One of the principal objects of this invention is to simplify a construction and arrangement of a bathtub drain and sump assembly and to improve the efficiency and operation thereof.

Another principal object is the provision of a drain and sump assembly for facilitating the rapid drainage of water, suds and the like from the tub.

Also it is a principal object to provide a drain and sump assembly wherein the sump is easily accessible for cleaning and for the removal of any accumulation of foreign matter.

Still another principal object hereof resides in the provision of a drain and sump assembly wherein a strainer is so arranged as to provide an annular gutter between it and a depressed region of the tub bottom wall, and strainer being readily demountable to afford access to the sump.

A still further object hereof is to provide an assembly of the character contemplated herein, which assembly is constructed and arranged so that articles which may have passed through the strainer will be retained in the sump from which they may be retrieved before said articles are discharged into the waste pipe.

Additional objects, aims, and advantages of the present invention will be apparent to persons skilled in the art after the construction and operation of the drain and sump assembly is understood from the within description.

It is preferred to accomplish the numerous objects of this invention, and practice the same, in substantially the manner hereinafter fully described and as more particularly pointed out in the claims. Reference is now made to the accompanying drawings which form a part of this specification.

In the drawings:

Fig. 1 is a vertical side elevation of a bathtub showing the drain and sump assembly contemplated herein;

Fig. 2 is a fragmentary plan looking down at the outlet or drain end of the tub shown in Fig. 1; and,

Fig. 3 is a vertical section taken along the plane of line 3—3 on Fig. 2, and drawn to an enlarged scale.

The drawings are to be understood as being more or less of a diagrammatic character for the purpose of disclosing a typical or preferred embodiment of the invention contemplated here-

2

in, and in these drawings like reference characters identify the same parts in the different views.

The tub 5, as shown in Fig 1, has a rim 6 with an apron or panel 7 extending down therefrom to the floor of the room, and it has a generally flat bottom wall 8 which inclines downwardly toward the drainage end of the tub at the right in Fig. 1.

In the arrangement shown in Fig. 3 the lower region of the bottom 8 has an annular depression formed by a down-turned flange 9 with an annular inwardly extending shoulder 10 the radially inward portion of which terminates in down-turned lip 11 to provide a relatively wide drain opening D.

A strainer of novel construction is supported on shoulder 10 and comprising a metal stamping of the form shown in detail in Fig. 3. This strainer comprises a flattened dome shaped top 12 the central region of which is in approximately the plane of the tub bottom 8 and has a central aperture in the bottom of a countersink 13, the purpose of which will hereinafter be explained.

As shown in Fig 3, the strainer is of inverted cup-shape, having a depending annular side wall 14 that is interrupted by a plurality of recesses 15 which define egress openings. These egress openings are of such dimensions that they permit small articles and the like to pass therethrough. The spacing of the openings is such that supporting feet 14a are defined between them for maintaining the strainer top in desired relation to the tub bottom wall 8. The side wall 14 of the strainer is located in radially inward spaced relation from the flange 9 forming the depression, and the supporting feet 14a rest upon the shoulder 10 at the bottom of the depression. This arrangement is made in order to accelerate the flow and increase the volume of water out of the tub, and the strainer wall 14, being spaced from depression flange 9, provides an annular gutter G in the depression surrounding the strainer.

A sump mounting annulus or ring 16, having an inside diameter sufficient to receive the lower flange 11 of the depression, is placed against the under-surface of shoulder 10, and is permanently anchored thereto by welding as at 17 and 18. The outside diameter of annulus 16 is greater than the diameter of the depression so that the outer region of the annulus projects beyond the vertical plane of wall 9. This outer region of the annulus provides flange means for attachment of a basin-like sump 19 which has a greater diameter than the depression in the tub bottom wall 8. The upper edge of the sump has an in-

turned flange 20 projecting under annulus 16 where it is held in assembly therewith by means of bolts 21 passing through said flange and threaded into tapped openings in the outer region of the annulus 16. In order to prevent leakage, a gasket 22 is interposed between flange 20 and annulus 16 to seal the joint between these parts.

The basin-like bottom 23 on the sump 19 is apertured preferably at its center and an overflow drain pipe 24 is secured in said opening by welding as shown at 25 and 26. This pipe 24 projects up into the sump a suitable distance and prevents articles which may fall into the sump, through the strainer recesses 15, from being discharged into drain pipe 24.

For the purpose of demountably supporting the strainer 12 on the shoulder 10 the sump has a cross piece or spider 27 below the horizontal plane of the lower edge of depression flange 11 and at its central region the cross piece has an upstanding boss 28 which is centrally bored and tapped as at 29. As clearly shown in Fig. 3, the top of boss 28 is immediately below the strainer countersink 13, and its upper end has a tapered recess 30 which provides a seat for said countersink 13. A round-head screw or bolt 31 is inserted through the central aperture in the countersink 13 and is turned into the threaded bore 29 until the head seats in said countersink, thus firmly but demountably securing the strainer in position against the shoulder 10.

From the foregoing it will be seen that the drainage of water from the bottom of the tub is quite rapid and any articles which may reach in the gutter G and then through recesses 15 into the sump will in most instances gravitate to the bottom of the sump, but the water will accumulate in the sump until it spills over the top of drain pipe 24 for disposal. It is thereafter a comparatively simple operation to remove the articles from the sump merely by unscrewing bolt 31 and lifting the strainer 12 from the shoulder 10, thus giving ready access to the sump for the removal of articles, as well as for cleaning the sump of extraneous matter such as sediment and the like.

While this invention has been described in detail in one of its preferred forms or embodiments, it will be apparent to persons skilled in the art, after understanding the improvements contemplated herein, that various changes and modifications may be made therein without departing from the spirit or scope thereof. It is aimed in the appended claims to cover all such changes and modifications.

What is claimed is:

1. A bathtub, basin, and the like having an apertured depression in its bottom defined by a pendent wall, an inturned shoulder and a discharge opening; a strainer in said depression comprised of a top wall at least a portion of which is proximate the plane of the tub bottom and having an apertured countersink, and apertured supporting means depending from said top wall and arranged on said shoulder in radially inwardly spaced relation to the pendent wall of said depression; an annulus anchored to the underside of said shoulder with its outer region projecting radially outwardly beyond the pendent wall of said depression; a sump having an inturned flange extending beneath said outer region of said annulus; means detachably securing said sump flange to said annulus; an overflow drain pipe having an end extended upward into said sump; a spider arranged transversely across

said sump in a plane above the top of said drain pipe; an upstanding axial boss on said spider having a threaded bore and having a recessed upper end seating said strainer countersink; and a screw inserted through said strainer with its head seated in said countersink and with its shank engaged in the threaded bore of said boss.

2. A bathtub, basin, and the like having an apertured depression in its bottom defined by a pendent wall, an inturned shoulder and a discharge opening; a strainer in said depression comprised of a top wall having an apertured countersink, and apertured supporting means depending from said top wall and arranged on said shoulder in radially inwardly spaced relation to the pendent wall of said depression; an annulus anchored to the underside of said shoulder; a sump secured to said annulus; an overflow drain pipe communicating with said sump above the bottom of the latter; a transverse member in the upper region of said sump, said member having a threaded bore aligned with said strainer aperture; and a screw inserted through said strainer aperture with its head seated in said countersink and with its shank engaged in the threaded bore.

3. A bathtub, basin, and the like having an apertured depression in its bottom defined by a pendent wall, an inturned shoulder and a discharge opening; an inverted cup-shaped strainer having an apertured side wall resting on said shoulder and spaced radially inward from said pendent wall to define a gutter in said depression surrounding said strainer; a sump connected to and depending from said inturned shoulder; an overflow drain pipe having an end extended upward into said sump; a cross member on said sump above said drain pipe; and means attaching said cross member to said strainer for demountably maintaining said strainer on said depression shoulder.

4. A bathtub, basin, and the like having an apertured depression in its bottom defined by a pendent wall, an inturned shoulder and a discharge opening; an inverted cup-shaped strainer in said depression, the top wall of said strainer having an apertured countersink, and the side wall of said strainer being recessed and supported on said shoulder in radially inwardly spaced relation to the pendent wall of said depression to define an annular gutter; a sump having a flange at its top beneath said shoulder and carried thereby; means for draining said sump; a spider arranged transversely across said sump in a plane above said drain means; a post on said spider having a bore with a countersunk upper end seating said strainer countersink; and securing means coacting with said strainer aperture and the bore of said post for demountably maintaining said strainer on said depression shoulder.

5. A tub, basin, and the like having an apertured depression in its bottom defining a discharge outlet; a shoulder at the bottom of said depression surrounding said outlet; an inverted cup-shaped strainer having an apertured side wall supported on said shoulder, the diameter of said side wall being less than the diameter of said depression whereby a gutter is provided surrounding said strainer; a sump carried by said shoulder beneath said depression in communication with said discharge outlet; and an overflow means communicating with said sump through a wall of the latter.

6. A tub, basin, and the like having an apertured depression in its bottom defining a dis-

charge outlet; a shoulder surrounding said outlet below the plane of the tub bottoms; an inverted cup-shaped strainer having a top wall approximately in the plane of the tub bottom and having an apertured side wall supported on said shoulder, the diameter of said side wall being less than the diameter of said depression whereby a gutter is provided surrounding said strainer; a sump carried by said shoulder beneath said depression in communication with said discharge outlet; and an overflow drain pipe extending up through the bottom wall of said sump.

7. A tub, basin, and the like having an apertured depression in its bottom defining a discharge outlet; a shoulder surrounding said outlet below the plane of the tub bottom; flange means projecting outward from said shoulder; a strainer supported on said shoulder, said strainer being comprised of a top wall, and a cylindrical side wall having recesses extending upward from its lower edge, the diameter of said cylindrical wall being less than the diameter of said depression whereby an annular gutter is provided which is drained through said recesses; a sump carried by said flange means beneath said depression in communication with said discharge outlet; and an overflow drain pipe communicating with said sump through a wall thereof.

8. A tub and the like having a bottom with an apertured depression therein defined by a depending wall, an inwardly extending shoulder member surrounding a central opening, and hav-

ing an outwardly extending flange member; a strainer comprised of a top wall at least a portion of which is approximately in the plane of the tub bottom, and apertured supporting means depending from said top wall and arranged on said shoulder member in radially inwardly spaced relation to the depending wall of said depression thereby defining a gutter surrounding said strainer; a sump having a radial flange cooperatively associated with said outwardly extending flange member and secured thereto; an overflow drain pipe having an end extending upward into said sump; a fixed cross member beneath said strainer top wall; and means inserted through said strainer top wall and engaged with said cross member for maintaining said strainer in position on said shoulder member.
